HAT HANGER

William E. Stephenson and Noral B. Mithun,
Missoula, Mont.

Application April 17, 1950, Serial No. 156,252

4 Claims. (Cl. 211—32)

1

This invention relates to garment receptacles and more particularly to a novel and efficient means for hanging hats which have been cleaned and blocked.

An object of the invention is the provision of an expendable hanger device preferably made of cardboard and which will retain a hat in an unsoiled and uncrushed condition.

Another object of the invention is the provision of a hook supported sheet of material having a crown receiving aperture therein and associated flaps for retaining and protecting the brim and crown portions of a hat.

A further object of our invention is to present a hat hanging device which is inexpensive to manufacture but which may nevertheless be used over and over for a long period of time both in the cleaning establishment and in the home. This device is not only of assistance to the merchant, in handling and transporting the cleaned article, but its utility to the customer encourages business and the hanger offers an outlet for good will and advertisement.

Still other objects and advantages will become apparent from the following description of the present invention illustrated in the accompanying drawings in which:

Figure 1 is a perspective view showing one modification of the invention.

Figure 2 is a plan view of the form of the invention shown in Figure 1 as stamped from a sheet of material.

Figure 3 is a bottom view of a cardboard form used in connection with the present invention to hold and support the shape of the hat.

Figure 4 is an elevation view of the form shown in Figure 3.

Figure 5 is a perspective view showing another modification of the invention.

Figure 6 is a plan view of the hanger shown in Figure 5.

Figure 7 is a sectional view taken on line 7—7 of Fig. 6.

Similar reference characters represent similar parts in the several figures.

At the present time it is customary for cleaning establishments to deliver articles such as hats in large paper bags. The cost of the conventional hat box makes its use impractical for this type of service. The use of a paper bag presents a number of problems during the handling of the garment, in that great care must be taken both during the storing and transporting of the hat to see that no object is placed on the top of the bag, thereby destroying the shape of the recently

2

cleaned and blocked hat. Furthermore, when the hat is ultimately received by the customer from the cleaning establishment the problem then arises of finding a sufficient place to lodge the hat where it will be free from damage until worn. Far too frequently between the cleaning and the wearing of the hat soiling or crushing occurs to the dissatisfaction of both the cleaning establishment and the customer. The present invention has been devised with this problem in mind and we have presented both a novel and inexpensive method, which is of considerable help both to the service establishment and to the customer.

15 While this hat hanger may be made from any number of types of materials the preferred and certainly the most feasible material which we have used is cardboard. As best seen in Fig. 2 of the drawings, the entire hat hanger may be stamped in one operation from a single sheet of cardboard and will present the general configuration as shown in Fig. 2 when completed. This modification may be for a matter of convenience, termed a deluxe or senior model since it has a greater number of elements and accordingly offers greater protection for the hat. It consists basically of two panels of cardboard 10 and 11 connected by means of a reduced neck portion 12 which acts as a convenient hinge between the two panels. On the upper end of the front panel 11 is formed a conventional hanging hook 13. Hook 13 has an inner arcuate edge 14 which fits over the conventional clothes rod or pole in the cleaning establishment, the cleaning truck or in the home.

30 In the central portion of panel 11 is a hat receiving aperture defined along its longitudinal edges by oppositely disposed arcuate cut lines 15 and 16, that portion of panel 11 lying between lines 15 and 16 is further divided by means of a transverse cut line 17. While a specific configuration of line 17 has been shown in the drawing, it is of course to be understood that any convenient configuration may be selected for this line. When 35 the cut line 17 has been made the portion between lines 15 and 16 is thus divided into two segments 18 and 19. It will thus be seen that when a hat is inserted from one side of panel 11 flaps 18 and 19 may be bent outwardly along lines 20 and 21, respectively, to form protective flaps for the crown of the hat.

40 After the hat has been inserted through the aperture in panel 11, as shown in dotted lines in Figure 1 of the drawing, the brim of the hat is 45 retained in place by means of a pair of oppositely

disposed small flaps 22 and 23. These small flaps or tabs are cut directly from the material which goes to make up panel 11 and are bent along lines 24 and 25 respectively, in a direction opposite to the crown protecting flaps 19 and 20. As best seen in Fig. 1 of the drawings, flaps 22 and 23 retain the hat in an inserted position within the aperture in panel 11. The resistance to bending of the hinge lines 24 and 25 of these small flaps will cause the hat to be retained within the aperture until such time as it is desired to remove the hat whereby flaps 22 and 23 may then be bent out of place and the brim of the hat released.

The free end of panel 10 of the hat hanger is provided with the spacing flange 26 similar in size and shape to the hinge member 12 previously described. At each end of flange 26 there is provided a hook-shaped connecting tab 27 having a hook portion 28 pointing inwardly toward the longitudinal axis of the hanger device. Each tab 27 may be bent along line 29 and folded downwardly to be engaged in a receiving slot 30 formed in panel 11 of the hanger. These slots 30 are inclined and adapted to receive the hook portions 28 of the connecting tabs. As best seen in Fig. 1 of the drawing when tabs 27 are inserted within slot 30 the hat hanger then becomes a box-like structure completely encircling the brim of the hat. Panel 11 is likewise provided with a pair of oppositely disposed spacing flanges 31 located on each side of the hanger element 13.

Another element of the invention is shown in Figs. 3 and 4 of the drawing. This element consists of a cardboard form having a dome-like configuration corresponding to the inner surface of the crown portion of the hat. The form consists of two separate sheets of cardboard 32 and 33 each sheet being flat along its lower edge 34 and having an upper arcuately curved edge 34a. One sheet is cut along its central axis half way up from its bottom edge and the other sheet is cut along its central axis half way down from its top edge. This enables one sheet to be slipped over the other in order to permit the cross construction shown in Figure 3 much in the same manner as the conventional cardboard compartments of an egg crate. At the bottom edge of sheet 32 are formed a pair of flanges or flaps 35 and 36. These flanges may be folded to extend horizontally in opposite directions. Likewise on the lower edge of sheet 33 are formed flanges 37 and 38 which are folded in opposite directions.

Flanges 35 and 36 are provided with small longitudinal slits 35a and 36a, respectively. This enables flange 35 to engage its adjacent flange 37 on the other sheet, and also enables flange 36 to engage its corresponding flange 38. This method of providing holes and slots enables the form to be held together as a single element so that it may be conveniently used.

As shown by the dotted lines in Figure 1 the form comprising sections 33 and 32 is placed within the hat crown. The hat is then inserted through the receiving aperture in panel 11 thereby forcing retaining flaps 19 and 20 outwardly as shown in Figure 1. Next the hat brim is threaded within the flaps 22 and 23 on the reverse side of panel 11 in order that the hat may be retained in the aperture. Panel 10 is then folded upwardly to completely encase the hat brim and the hook tabs 27 are bent downwardly and inserted within slots 30 and panel 11. Thus the hat is completely retained within the hat hanging device.

A more simple modification of the invention is shown at 39 in Fig. 5 of the drawing. This form of hat hanger may be conveniently termed a "junior" model since it in reality contains only a single cardboard panel 40. Similar to the other modification the hanger 39 contains a hook element 13a, a hat crown receiving aperture and a pair of oppositely disposed crown flaps 18a and 19a. The arcuate edges 15a and 16a of the hat receiving aperture may if desired be provided with a plurality of radial slits 41. This permits the aperture to adapt itself to larger size hat crowns and assists in retention of the hat within the hanger device.

Rim retaining flaps 22a and 23a are likewise provided in this modification. As seen in Fig. 5 they effectively overlay the brim of the hat and retain the hat within the aperture of the hanger device.

The convenience and utility of this device will be readily seen. It is intended that when the hat and holder are placed in a paper bag, the hook end 13 will extend out of the bag opening, and the corners of the bag may be folded over and fastened. The hat may then be conveniently hung in the laundry, in the truck of the delivery driver or in the home of the customer. The hat which has been cleaned and blocked will remain free from dirt or crushing at all time, during delivery or storage of the hat. This naturally insures greater satisfaction with the cleaning service provided by the merchant. The actual cost of the hanger to the merchant is insignificant and for this reason may be deemed expendable by him. Thus the hanger may be retained by the customer for future use and as a constant reminder of the satisfactory service of the cleaning establishment. The provision of sufficient area on the hanger for advertising material provides the customer with a permanent reminder of the services available by the merchant.

While a preferred form of the invention has been shown and described, it will be understood that variation in details of form may be made without departure from the invention as defined in the appended claims.

We claim:

1. A hat hanger comprising a first panel of material having an aperture therein adapted to receive the crown of a hat, a hook formed on one end of said panel, a second panel of material hingedly connected to the end of said first panel opposite said hook, said second panel having a free end thereon, and means releasably connecting said free end of the second panel to the hook end of the first panel when the second panel is moved to a plane parallel to the first panel.

2. A hat hanger comprising a first panel of material having an aperture therein adapted to receive the crown of a hat, a hook formed on one end of said panel, a second panel of material hingedly connected to the end of said first panel opposite said hook, said second panel having a free end thereon, hook shaped tabs on said free end, the hook end of the first panel having slots formed therein for receiving said tab when the second panel is positioned in a plane parallel to the first panel.

3. A hat hanger comprising a sheet of material, the central portion of said sheet being cut into segments, each of said segments having an uncut edge hingedly attached to the sheet, and each being pivotally movable outwardly from the plane of said sheet, said sheet having an aperture formed by pivotal displacement of the seg-

ments, said segments substantially closing said aperture when lying in the plane of said sheet, said segments extending outwardly of said plane of said sheet adjacent said aperture and adapted to protect the crown of a hat received in said aperture.

4. A hat hanger comprising a sheet of material, the central portion of said sheet being cut into segments, each of said segments having an uncut edge hingedly attached to the sheet and each being pivotally movable outwardly from the plane of said sheet, said sheet having an aperture formed by displacement of the segments, said segments substantially closing said aperture when lying in the plane of said sheet, and hat rim retaining flaps on said sheet, said segments extending outwardly of said plane of said sheet

5
adjacent said aperture and adapted to protect the crown of a hat received in said aperture.
